CLAIM

The ornamental design for an ultrasound transducer, as shown and described.

DESCRIPTION

FIG. 1 is a top-front-left perspective view of an ultrasound transducer showing my new design;

FIG. 2 is a bottom-front-left perspective view thereof;

FIG. 3 is a top-rear-right perspective view thereof;

FIG. 4 is a bottom-rear-right perspective view thereof;

FIG. 5 is a front elevational view thereof;

FIG. 6 is a rear elevational view thereof;

FIG. 7 is an enlarged top plan view thereof;

FIG. 8 is an enlarged bottom plan view thereof;

FIG. 9 is a left elevational view thereof; and,

FIG. 10 is a right elevational view thereof.

The broken lines showing a cable end in FIGS. 1-6 and 8-10 are included for the purpose of illustrating environmental structure and form no part of the claimed design.
